US00D592689S

(12) **United States Design Patent**
Dunn

(10) **Patent No.:** **US D592,689 S**
(45) **Date of Patent:** **** May 19, 2009**

(54) **DIGITAL MICROSCOPE**

(75) Inventor: **Steven Dunn**, Leawood, KS (US)

(73) Assignee: **Ken-A-Vision Mfg. Co., Inc.**, Kansas City, MO (US)

(**) Term: **14 Years**

(21) Appl. No.: **29/327,044**

(22) Filed: **Oct. 29, 2008**

(51) **LOC (9) Cl.** **16-06**

(52) **U.S. Cl.** **D16/131**

(58) **Field of Classification Search** **D16/130, D16/131, 202, 203; 359/350, 368, 369, 376, 359/377, 379, 380, 381, 383, 385, 388, 390, 359/392, 363, 365, 391; 600/118; 250/311; D10/104; D21/483**

(57) **CLAIM**

The ornamental design for a digital microscope, as shown and described.

DESCRIPTION

FIG. 1 is an isometric view of a digital microscope showing my new design;

FIG. 2 is a top plan view of a digital microscope, the bottom of the ocular is not part of the claimed design;

FIG. 3 is front elevational view of the microscope;

FIG. 4 is a side elevational view of a digital microscope the opposite side is a mirror image;

FIG. 5 is a bottom view of the microscope; and,

FIG. 6 is a rear elevational view of the microscope.
